United States Patent Office

Des. 183,445
Patented Sept. 2, 1958

183,445

SPLICE BOX

Leonard Atkin, Springfield, N. J., assignor to Stone Manufacturing Co., a corporation of New Jersey

Application May 24, 1957, Serial No. 46,342

Term of patent 14 years

(Cl. D26—5)

FIG. 1.

FIG. 2.

FIG. 3.

FIG. 4.

I claim:

The ornamental design for a splice box, substantially as shown.
